executor for Wyllis Pierson,
deceased

James Head, & Lazarus H. Pierson, Exec. of Myllis Pierson Esq.

Letters Patent.

The Schedule referred to in these Letters Patent, and making part of the same, containing a description in the words of the said James Head, and Lazarus H. Pierson, Executor of the late Myllis Pierson deceased, themselves or their improvement in the "Lath cutting Machine."

To all to whom these presents shall come, greeting.

Be it known that I, James Head, of Lebanon, in Warren County and State of Ohio, together with Myllis Pierson by now deceased but late of said County, had in the lifetime of said Myllis, invented a new and useful improvement in the "Lath cutting Machine," and that the following is a full and exact description of the construction and operation of said machine, as invented by me, and the said Myllis Pierson deceased. The machine is constructed with two upright wooden posts which are connected at a suitable height by a substantial tie or brace. On the back part of each post and opposite to said tie or brace is placed a permanent arm designed to serve as a fulcrum, and to each of these arms is attached a lever with the long end upwards - At a proper distance above said tie or brace is a double crank each end of which is in one of the wooden posts, and is regulated at one end by a balance wheel. At or near each end of said crank are attached two pitons. One of said pitons at each end of said crank, or each side of the machine is horizontally attached to said crank and to the top ends of said levers. The other two of said pitons are attached perpendicularly to said crank and to the front or perpendicular knife in front of the aforesaid tie or brace. To the lower end of each of the aforesaid levers is attached a movable arm standing in rear and horizontal to which is attached the rear, or horizontal knife below said tie or brace. Immediately above the movable arms in the lower end of said knife is attached a flat hand and shoulder which

operates

operate on a ratchet wheel between the ends of the perpendicular knife and each fender post. These ratchet wheels are at the ends of a roller on which are placed two or more pinion wheels.

Above the back of the perpendicular knife two movable levers are attached; to the aforesaid tie, or braces, resting on arms or fulcrums on the roller aforesaid; at the front ends of said movable levers are attached weights to cause said pinion wheels to hold fast, operate and turn the log that is to be cut into laths.

The log is placed between the fender posts by means of a horizontal mandrel passing centrally through it, or by guides at each end.

The carriage is formed of two inclined planes parallel, and one placed near to each fender post, with cog or teeth on the upper side of each of said inclined planes; above which is placed the horizontal mandrel aforesaid with cog or teeth corresponding with those in the inclined planes in which they operate to turn the log and to propel the carriage. These cogs and teeth, and the angle of the inclined planes are so constructed that by beginning at the foot or lower end of the plane and moving forwards or upwards by means of the feed hands, ratchet pinion wheels and cog wheels aforesaid; that each revolution of the mandrel and log will raise the log on the inclined planes, or carriage the width of the laths.

When the machine is put into operation by means of my power, the turning of the aforesaid double crank causes the pitman attached to the upper end of said levers to pass outwards by which means the rear or horizontal knife is forced inwards, and cuts the thickness of a lath. The crank continuing to turn operates on the perpendicular pitman and forces the perpendicular knife downwards and cuts the width of a lath, and by these two operations cutting a lath entirely out of the log, and by the turning of the double crank and the operation of the feed hands on the ratchet wheels the pinion roller turns the log, which turns the mandrel and moves the carriage up the thickness of a lath, and then the knife operates aforesaid, and so on until the log is entirely cut into laths.

Witnessed
